CLAIM

The ornamental design for a part of rinsing machine for barrels, as shown and described.

DESCRIPTION

FIG. 1 is a front perspective view of a part of rinsing machine for barrels, showing the new design;

FIG. 2 is a top perspective view thereof;

FIG. 3 is a left side perspective view thereof;

FIG. 4 is another front perspective view thereof;

FIG. 5 is a left side perspective view of a top portion of the part of rinsing machine for barrels;

FIG. 6 is another left side perspective view of the top portion thereof;

FIG. 7 is another left side perspective view of the top portion thereof;

FIG. 8 is a front perspective view of the top portion thereof;

FIG. 9 is a top perspective view of the top portion thereof;

FIG. 10 is another top perspective view of the top portion thereof; and,

FIG. 11 is another top perspective view of the top portion thereof.
